CLAIM

The ornamental design for a divider for a cattle stall, substantially as shown and described.

DESCRIPTION

FIG. 1 is a perspective view of a divider for a cattle stall showing our new design;

FIG. 2 is another perspective view thereof, on an enlarged scale;

FIG. 3 is an elevational view taken from one side thereof, the opposite side being a mirror image of the side shown;

FIG. 4 is a rear elevational view thereof;

FIG. 5 is a front elevational view thereof;

FIG. 6 is a top plan view thereof; and

FIG. 7 is a bottom plan view thereof.

The fragmentary broken line representation of cattle stalls in FIG. 1 is for purposes of illustration only.
